Des. 219,584
Patented Dec. 29, 1970

219,584

BUCKET SEAT

Steven T. McQueen, Los Angeles, Calif.
(14732 Oxnard St., Van Nuys, Calif. 91401)

Filed Dec. 8, 1969, Ser. No. 20,416

Term of patent 14 years

Int. Cl. D6—01
U.S. Cl. D15—8

Fig. 1

Fig. 3

Fig. 2

Fig. 4

Fig. 5

FIG. 1 is a front perspective view of a bucket seat embodying my new design;

FIG. 2 is a side elevational view thereof;

FIG. 3 is a front elevational view thereof;

FIG. 4 is a top plan view thereof; and

FIG. 5 is a rear elevational view thereof.

I claim:

The ornamental design for a bucket seat, as shown.
